United States Patent Office.

WALTER WARD, OF MOUNT HOLLY, NEW JERSEY.

Letters Patent No. 94,261, dated August 31, 1869.

IMPROVEMENT IN WRENCH.

The Schedule referred to in these Letters Patent and making part of the same.

To all whom it may concern:

Be it known that I, WALTER WARD, of Mount Holly, in the county of Burlington, State of New Jersey, have invented certain new and useful Improvements in Wrenches; and I do hereby declare the following to be a full, clear, and exact description thereof, reference being had to the accompanying drawings, making part of this specification, and in which—

Figure 1 is a side view of my improved wrench, with the handle shown in two positions;

Figure 2 is a perspective view of the handle and one jaw; and

Figure 3, a perspective view of the other detached jaw.

I am aware that very many improvements have been made in this class of invention, and many of them highly useful and practical, but I believe that my present invention is more simple and practical, and less liable to get out of repair, than any known, and at the same time more economic of manufacture.

To enable those skilled in the art to make and use the same, I will proceed to describe the construction and operation of the same, referring by letters to the accompanying drawings.

Similar letters of reference denote like parts in the different figures.

A represents the handle, which is pivoted to the upper jaw B by pin *a*, the said jaw B being slotted out to receive the end of said handle.

The handle A, at the end attached to the jaw, is extended upward a short distance, as seen in the drawings, and terminating in a tooth or point, *b*, the handle becoming, as it were, a pawl swinging upon the pivot *a*.

The lower jaw C is provided with an arm, D, one end of which is of ratched-form a part of the whole of its extent. The rear end of the jaw, if deemed expedient, may also be serrated to enable the two jaws to be brought in immediate contact with each other.

The upper jaw B is mortised, as seen at *d*, to allow the arm D of the jaw B to pass through the same,

so that it will be observed the faces of the two jaws are always moved in parallel planes.

The operation of my improved wrench is as follows:

The face of the jaw B being placed upon one side of a nut, the rear end of the handle A being elevated, the point or tooth *b* is carried away from the ratched face of the arm D, which is then allowed to move freely through the slot *d* of the jaw B. Said jaw is then forced up against the opposite side of the nut, when the handle is depressed or allowed to drop, to the same place in which the face of the jaw B lies, and consequently the tooth or point *b* engages with the ratchet-edge of the arm D, and the nut turned, it being observed that the greater the force exerted at the rear end of the arm or handle A, the tighter the pawl grasps the arm D, its tendency being to force the arm through the slot *d*, and thus force the faces of the two jaws to approach each other.

By this construction of a wrench, all screws and threads, both male and female, are done away with, as well as any cogged gearing, avoiding any backlash and wear, as well as sloth in adjustment.

My wrench is capable of almost immediate adjustment, and is so constructed that each and every part may be duplicated at slight cost, so that the breaking of any one part does not render the whole useless, as the broken part may be replaced by a new one.

Having described the construction and operation of my improved wrench,

What I claim as new, and desire to secure by Letters Patent, is—

The handle A, with its tooth *b*, engaging in the ratchet, on bar D, of jaw C, and operating substantially as described.

In testimony whereof, I have hereunto set my hand, this 6th day of July, 1869.

WALTER WARD.
